UNITED STATES PATENT OFFICE.

LUCENA M. MORDEN, OF WATERBURY, CONNECTICUT.

TEMPORARY BINDER.

No. 870,837.

Specification of Letters Patent.

Patented Nov. 12, 1907.

Application filed June 1, 1906. Serial No. 319,679.

To all whom it may concern:

Be it known that I, LUCENA M. MORDEN, a citizen of the United States, of 59 Grand street, Waterbury, county of New Haven, and State of Connecticut, have 5 invented certain new and useful Improvements in Temporary Binders, fully described and represented in the following specification and the accompanying drawings, forming a part of the same.

The file binder in the present invention comprises a 10 base, a ring-section held stationary thereon, a ring-section complementary thereto pivoted upon the base, and a cam operated to press the hinged section toward the fixed section. In practice, a plurality of such devices are combined with a single base to engage a plurality of holes in the edges of perforated sheets, thereby 15 holding them detachably together for use in the binder.

The invention will be understood by reference to the annexed drawing, in which

Figure 1 is a plan of the fixtures; Fig. 2 is an edge 20 view of the same; Fig. 3 is an end view of the same with the rings closed; and Fig. 4 an end view with the rings open.

The base *a* is shown of sheet-metal, with cam-shaft sockets *b* at one edge having a cam-shaft *c* journaled 25 therein. The base has a longitudinal flange *d* along the opposite edge, and ears *e* are cut from notches *e'* in the base and bent upwardly in pairs, and the ring-sections *f* and *g* are attached together upon a pivot *h* and are complementary to one another so as to form a 30 complete ring when closed.

The section *g* is held stationary by having its shank rest upon the base and upon the flange *d*, and it is held stationary by lugs *i* bent inwardly from the tops of the ears *e*. The section *f* is movable, and its shank adjacent to the pivot *h* lies over the cam-shaft *c*, and a cam 35 *c'* is formed upon the shaft adjacent to each of such sections and proportioned to press such sections against the stationary sections *g*, and hold the movable sections locked, as in Fig. 3.

40 A spring *k* is provided to press each of the movable pivot-sections *f* normally apart from the stationary sections, so that when the cams are turned outwardly as shown in Fig. 4, the sections are automatically opened to remove or change the perforated sheets. Such wire 45 spring is conveniently supported at the side of the movable section upon one of the ears *e* by means of bent teeth *l* punched from the ear and overlapped upon the body of the wire.

By the construction described, the pivot-bearings 50 for the ring-sections and the socket-bearings for the cam-shaft are all formed integral with the base, and are readily cut and stamped therefrom by suitable tools. The cam-shaft and the cams are readily made integral

by bending cranks or offsets upon the shaft as shown in Fig. 2, the end of the shaft being bent transversely, 55 or looped to form a handle for turning the same. The handle is so related to the cams that it lies upon the base out of the way, as shown in Fig. 1, when the ring-sections are closed.

In manufacturing the base, it is formed with projections *b'* indicated by dotted lines in Fig. 1, which may be readily bent over the journals of the cam-shaft, as shown in full lines in Figs. 1 and 4, at the interspaces between the cranks or cams *c'*. The base *a* is shown narrower than the diameter of the rings, so that the 65 fixed sections *g* project over the flange *d*, which is notched to fit the under side of the ring and hold it laterally. It will also be observed that the transverse arrangement of the ring-sections upon the base 70 enables the cam-shaft to be extended along the edge of the base, and that the cams operate to lock the movable sections *f* when they are rocked toward the sections *g*, as shown in Fig. 3.

The construction is very cheap to manufacture, and operates very quickly and conveniently in opening and 75 closing the ring-sections.

Having thus set forth the nature of the invention what is claimed herein is:

1. In a temporary binder, the combination, with a longitudinally extending base, of complementary ring-sections 80 supported transversely upon the base, one section of each ring secured immovably upon the base and projecting over one edge of the same, and the other section of each ring being pivoted upon the base to rock transversely, a cam-shaft extended along the edge of the base beneath such 85 movable ring-sections, cams upon the shaft operating to close and lock such movable sections, and a spring arranged and operated to open the movable sections when the cam is turned to release the same.

2. In a temporary binder, the combination, with a base 90 having cam-shaft sockets along one edge and a series of pivot-bearings projected upward therefrom, of a series of ring-sections pivoted movably upon the said bearings, a shaft journaled in the sockets and having a cam to move each of such pivot sections, and complementary ring-sections 95 united to the pivot and held immovably upon the base, forming a series of closed rings with the pivot-sections when the cam is operated.

3. In a temporary binder, the combination, with a sheet-metal base having a series of integral transverse ears bent 100 upward from the base to form pivot-bearings and having locking lugs thereon, of ring-sections pivoted movably upon the ears, complementary ring-sections held stationary upon the base by engagement with the pivots and with the locking lugs, and means for moving the pivot-sections to 105 and from the stationary sections.

4. In a temporary binder, the combination, with a sheet-metal base having a series of integral transverse ears bent upward from the base to form pivot bearings and having locking lugs thereon, of ring-sections pivoted movably 110 upon the ears, complementary ring-sections held stationary upon the base by engagement with the pivots and locking

lugs, wire springs secured upon the upturned ears and operating to hold the pivot-sections normally open and means for moving the pivot-sections toward the stationary sections.

5 5. In a temporary binder, the combination, with a sheet-metal base having cam-shaft sockets along one edge, and an upturned flange at the opposite edge, with a series of ears bent upwardly from the base to form pivot-bearings, of a series of ring-sections pivoted movably upon the said 10 bearings, a shaft journaled in the sockets and having a

cam to move each of such pivot-sections, and complementary ring-sections held stationary upon the base by engagement with the pivot and contact with the base and its flange.

In testimony whereof I have hereunto set my hand in the presence of two subscribing witnesses.

LUCENA M. MORDEN.
